UNITED STATES PATENT OFFICE.

KONSTANTINE THULANDER AND VICTOR B. NELSON, OF ROCKFORD, ILLINOIS, ASSIGNEES TO NATIONAL LOCK COMPANY, OF ROCKFORD, ILLINOIS, A CORPORATION OF ILLINOIS.

DESK-FALL SUPPORT.

1,205,411.

Specification of Letters Patent. Patented Nov. 21, 1916.

Application filed February 3, 1913. Serial No. 745,812.

To all whom it may concern:

Be it known that we, KONSTANTINE THULANDER, a subject of the King of Sweden, and VICTOR B. NELSON, a citizen of the 5 United States, residing at Rockford, in the county of Winnebago and State of Illinois, have invented certain new and useful Improvements in Desk-Fall Supports, of which the following is a specification.

10 Our invention relates to supports for desk falls, and may be used in all cases where it is desired to apply supporting means to the outer edge of a hinged element.

The object of our invention is to provide 15 a desk fall support which will open to a desired position in either direction, and hence may be used either as a right-hand or left-hand support. Such supports have heretofore been made with a stop operating in but 20 one direction, thus necessitating the manufacture and use of a different support for each end of the desk fall. The interchangeability of our support is a valuable feature, as it obviates the necessity of carrying 25 different kinds of supports in stock, avoids mistakes in filling orders for repairs, and facilitates the assembling of the desk parts.

In the accompanying drawings, Figure 1 is a perspective view of a desk fitted with 30 our improved device. Fig. 2 is a fragmental side elevation of our device when opened as a right-hand support. Fig. 3 is a section on the line 3-3 of Fig. 2. Fig. 4 is a representation of the same device partially folded and 35 being changed from a right-hand to a left-hand support. Fig. 5 shows the same device opened as an inverted left-hand support, the turning movement indicated in Fig. 4 having been completed. Fig. 6 is a 40 perspective view of the stop plate of the device. Fig. 7 is a fragmental perspective view on a reduced scale showing the method of attaching the support to the desk fall leaf.

45 In the embodiment of our invention here illustrated, the desk 7 has ends 8 and 9 and a hinged fall leaf 10 supported at either end by our improved interchangeable supports, which supports comprise an upper arm 11, 50 a lower arm 12 pivotally connected with the arm 11, and a stop plate 13. The upper arm 11 is perforated for pivotal attachment to the desk end 8 or 9; and the lower arm 55 may be pivotally connected in any suitable manner with the fall leaf 10. In the embodiment

ment herein shown this attachment is effected by means of a small bracket plate 14 pivotally connected with the arm 12 by means of a bolt or rivet 14^a, and perforated for rigid attachment to the fall leaf 12. In 60 order to clear the end of the desk the upper arm 11 is slightly offset at 15 just below the point of attachment to the desk.

In the prior art the stop which prevents the unfolding support from reaching or 65 passing dead center has been formed on one of the arms near the point of intersection. Inasmuch as the offset at 15 is necessary and the bracket plate 14 must be on the inner side of the arm 12, it is obvious that a support opening in but one direction could be used on but one end of the desk, thus necessitating the manufacture of a right-hand and left-hand support, as above stated. We have overcome this necessity by forming 70 75 the stops in such a manner that the arms may open in either direction to the same predetermined extent, short of a dead center. This may be accomplished in various ways. In the specific embodiment of our invention 80 herein shown, we have formed the stop on the stop plate 13 which is placed between the ends of the arms 11 and 12, perforated and loosely centered on a rivet 16 by which also the said ends are pivotally connected. 85 The stop plate 13 is formed with three lugs or stops 17, 18 and 19, two of which, 17 and 18, are adapted to engage the upper arm 11 while the lug 19 is formed in a reverse direction to engage the lower arm 12. 90

When in use as a right-hand support the position of the parts is shown in Fig. 2, and as adapted to the right-hand end of the desk, in Fig. 1. The descending fall leaf 10 opens the arms 11 and 12, turning on the pivot 16 until the stop 18 coming in contact with the arm 11 and the stop 19 engaging the arm 12, the limit of the opening movement is reached before the arms have reached a dead center position, thus making it possible to fold the 100 support again by raising the fall leaf 10. In this position the stop 17 is idle. When it is desired to use the same support on the left-hand end of the desk, the arm 12 is rotated past the arm 11, as indicated by the arrow in 105 Fig. 4, until it reaches the position shown in Fig. 5, the arm 11 being shown in the same position in Figs. 2, 4 and 5. The stop 17 is then in contact with the arm 11, and the stop 19 engages the side of the arm 12 opposite to 110

that which it engaged in Fig. 2, the stop 18 now being idle. The action of the stop 17 and 19 limits the opening movement of the arms. The relative position of the arms being reversed, the offset at 15 and the bracket plate 14 are oppositely faced, and the support is adapted to be attached to the left-hand end 8 of the desk 7, as shown in Fig. 1.

The stop plate 13 is made two-thirds round, so that in either open position one of its straight edges lies parallel with one edge of the arm 12, thus adding to the neat appearance of the device.

It is obvious that details of construction may be varied without departing from the spirit of our invention.

Having thus described our invention, we claim:

1. A reversible desk-fall support comprising two pivotally connected arms, a stop-plate rotatably mounted between said arms and adapted to limit the opening movement of said arms in either direction, and a lug pivoted at the end of one of said arms and adapted to form a reversible connection with the desk-fall.

2. A desk fall support comprising pivot-

ally connected arms and a rotatable stop plate adapted to prevent said arms from opening in either direction to a dead center. 30

3. In a desk fall support, two pivotally connected arms and a stop plate rotatably mounted between said arms and adapted to limit the opening movement of said arms in either direction. 35

4. In a desk fall support, two pivotally connected arms, and a stop plate interposed between said arms having two stops on one face and one stop on the opposite face.

5. In a desk fall support, two pivotally connected arms and a stop plate rotatably mounted between said arms and having two oppositely positioned stops adapted to engage either side of one of said arms, and a single stop adapted alternately to engage either side of the other arm. 40 45

In testimony whereof we affix our signatures in the presence of two witnesses.

KONSTANTINE THULANDER.
VICTOR B. NELSON.
